VEHICLE OPERATED CATTLE GATE

Frederick W. Bosch, Worland, Wyo.

Application June 4, 1951, Serial No. 229,743

5 Claims. (Cl. 39—91)

1

My invention relates to improvements in vehicle operated cattle gates, of the horizontally pivoted vertically swingable type.

The primary object of my invention is to provide a mobile gate, of the type indicated, for moving into different locations and which is equipped for easy opening and constructed and arranged for self closing with a retarded action so as to give a vehicle ample time to pass through the gateway before the gate is closed.

Another object is to provide a gate of the character and for the purposes above set forth which is adapted to be both unlatched and opened by a vehicle approaching the same and which is comparatively simple in construction, foolproof, and inexpensive to install and manufacture.

Still another object is to provide in such a gate for overcoming wind resistance to opening and closing movement of the gate.

Other and subordinate objects, within the purview of my invention, together with the precise nature of my improvements, will be readily understood when the succeeding description and claims are read with reference to the drawings accompanying and forming part of this specification.

In said drawings:

Figure 1 is a view in perspective of my improved gate in the preferred embodiment thereof with the gate closure in gate closing position;

Figure 2 is a view in side elevation of the same;

Figure 3 is a view in side elevation with the gate closure swung into complete gate opening position;

Figure 4 is a view in side elevation drawn to a larger scale, with parts in section, for better illustration of the details of the gate, the gate closure being shown in gate closing position;

Figure 5 is a fragmentary view in plan of the same;

Figure 6 is an enlarged fragmentary view in side elevation, partly in transverse section, illustrating in full and dotted lines the operation of the gate closure and other parts in the opening movement of said closure, and

Figure 7 is a fragmentary view in horizontal section taken on the line 7—7 of Figure 4 and illustrating the manner in which the rotor section of the gate closure, and the vane of the closure counterbalancing means are mounted on the rock shaft carrying the gate closure.

Referring to the drawings by numerals, my improved gate comprises a gate closure 1 mounted, as presently described, on an elongated rectangular skid carriage 2 to extend transversely of said carriage in the approximate center thereof. 55

2

The skid carriage 2 is particularly designed for sliding over the ground to dispose the gate closure 1 across a road 3, or the like. As illustrated, the skid carriage 2 comprises a pair of longitudinal, front and rear side runners 4, 5 preferably of tubing, and which are secured together parallel by cross beams 6, 7 at the ends thereof and by a pair of intermediate similar cross beams 8, 9 upon opposite sides of the transverse center of said carriage 2 and contiguous opposite sides of the gate closure 1.

The gate closure 1 is mounted on the skid carriage by the following means. A pair of upright posts 10, 11 are suitably mounted at the ends of 15 the skid carriage 2 on the beams 6, 7, and a similar post 12 is suitably mounted on the intermediate cross beam 9, said posts being aligned in the longitudinal center of the skid carriage.

The gate closure 1 comprises a rear end, skeleton wheel, rotor section 13 including a hub 14, said hub being fixed by a set bolt 15 on a rock shaft 16 extending longitudinally of the skid carriage 2 and being suitably journaled on the tops of the posts 10, 11, 12 to dispose the gate closure 20 in approximately the transverse center of the carriage and provide a horizontal closure supporting shaft. The gate closure 1, in addition to the described skeleton section 13, comprises a C-shaped rear end, balance weight 17 extending around one-half of said section 13 and suitably fixed to the rim 18 thereof and to some of the spokes 19 of said section. The balance weight 17 is preferably formed of concrete, or the like. A pair of tubular arms 20 extend from the ends of the balance weight 17 and tangentially from the 35 rim 18 of said section 13 coplanar with said section and are suitably fixed thereto. The ends of a U-shaped closure frame 21, and which carries mesh wire 22, extend into said arms 20 and are suitably fixed therein by cross pins, as at 23. Obviously, the arrangement provides for removal of the closure frame 21 and replacement, as may be desired.

A wire stretcher bar 24, to which the mesh wire 22 is suitably connected is slidably mounted by 45 end sleeves 25 on the arms 20 for adjustment along said arms to stretch the mesh wire. Draw bolts 26 connect the stretcher bar 24 with a cross connecting bar 27 extending between the arms 28, said bolts being operative for adjusting said 50 bar 24 as will be manifest. Suitable transverse bars 28 connect opposite sides of the closure frame 21 for reinforcing purposes.

As shown in Figures 1 and 2, the gate closure 1, in the gate closing position thereof, extends 55 across the road 3 with its front end 29 confined

between pairs of keeper plates 36 on a gate post 31. In this position of the gate closure 1, the balance weight 17 is disposed on the side of the axis of the rock shaft 16 opposite said closure frame 21, so that said weight 17 balances said closure frame 21 for easy swinging of the gate closure 1 into gate opening and closing positions respectively. A barbed wire 32 attached to lugs 33 on the closure frame 21 tops said frame when said gate closure 1 is in gate closing position to act as a guard serving to prevent cattle from jumping the gate closure.

Latch mechanism is provided for latching the gate closure in gate closing position comprising the following. A latch bar 34 is pivoted at one end, as at 35, to one of the arms 28 which is lowermost when the gate closure is in gate closing position, said latch bar 34 swinging downwardly, under the influence of gravity, as said closure 1 nears closing position, and when said closure is in closing position having its free end disposed behind a front longitudinal abutment bar 36 on the skid carriage 2 and suitably secured to the crossbars 8, 9, the arrangement being such that said abutment bar 36 by engagement with the free front end of said latch bar 34 blocks upward swinging of the gate closure 1 towards opening position. The latch bar 34 is swingable upwardly, in the closing position of said gate closure, clear of the abutment 36 into unlatching position. A stop lug 37 on said lower arm 28 limits such swinging of the latch bar 34, for a purpose presently seen.

Vehicle operative means is provided for unlatching the latch bar 34 and then swinging the gate closure 1 towards gate opening position, and which will now be described. A pair of arms 40 are provided at the opposite ends of the front side runner 4 and are suitably attached in transverse position relative to the skid carriage 2 to the ends of a shaft 41 rotatably extended through said runner 4 so that said arms 40 are vertically swingable on the skid carriage 2 transversely thereof into horizontal lowered ground engaging position, or, into upstanding raised position and for a purpose presently seen. In the lowered position thereof, said arms 40 extend across and lie flat on the road 3 on opposite sides of the gate closure 1 a distance substantially greater than the over-all length of the usual road vehicle.

A pair of sleeves 42, formed of pipe, are rockably mounted on the rock shaft 16 upon opposite sides of the gate closure 1. A pair of right angularly related latch bar lifting and sleeve restoring levers 43, 44, respectively, are suitably fixed to the inner end of each sleeve 42, said levers 44 inclining upwardly and forwardly of the skid carriage 2 and said levers 43 inclining downwardly and forwardly of said carriage, when the gate closure is in gate closing position. As will be seen, the pairs of levers 43, 44, lie upon opposite sides of the gate closure 1.

A pair of coil springs 45 yieldingly connect the upper ends of the sleeve restoring levers 44 to the before mentioned connecting bar 27, as at 43', 44', and a pair of chains 46 connect the front ends of the latch bar lifting levers 43 to the free end of the latch bar 34, the arrangement being such that, upon initial rocking movement of the sleeves 42, in one and the same direction from a normal restored position, said levers 43 will first lift the latch bar 34 into releasing position to unlatch the gate closure 1 and engage said latch bar 34 with its stop lug 37, while levers 43 on the

sleeve move idly rearwardly and stretch the spring 45 attached thereto until said latch bar 34 is released. At this point, further rocking of either sleeve 42 in the same direction will cause the latch bar 34 through engagement with its stop lug 37 to swing the gate closure 1 upwardly toward gate opening position. The latch bar 34, chains 46 and stop lug 37 form lost motion means operatively connecting said sleeves 42 to the gate closure 1 with a delayed action.

A pair of pull chains 47 are attached, as at 48' at one end to the free ends of the arms 40 to extend across the road 3 and under the sleeve 42 when said arms are lowered, the other ends of the chains 47 being slidably connected to a pair of skeleton, substantially V-shaped cranks 48 extending, in the closing position of said closure 1, and the normal position of the sleeves 42, upwardly and rearwardly in vertical planes from the outer ends of the sleeves 42 to which said cranks are attached at one end. The other end of each crank 48 is fixed to a spacer and abutment 49 interposed between said end and the sleeve 42 and suitably fixed to said sleeve. The chains 47 are sufficiently slack to permit a vehicle to ride over and to press the same to the road 3 so as to exert pull against the cranks 48 and swing the gate closure 1 upwardly from closing position with sufficient momentum to swing into completely opened substantially horizontal position.

A rectangular, vertically swingable vane 51 having a normal horizontal position extends longitudinally of and opposite one sleeve 42 at the side of said sleeve opposite the gate closure frame 21 and serves a purpose presently explained. The vane 51 is mounted rigidly at one end on the balance weight 17 by an angle bar 52 bolted, as at 53, to said vane and, as at 54, to said weight, the other end of the vane 51 being bolted, as at 55, to an angle bar 56 formed on a sleeve 57 fixed on the rock shaft 16 by a pin 58. An end opening 59 in the van 51 accommodates one of the cranks 48 for a reason presently seen. A weight 60 is suspended from the sleeve 42 that is opposite the vane 51, and by a chain 61 fastened into a loop 62 freely slidable around said sleeve and which may be lengthened or shortened for a purpose to be explained.

On the side of the skid carriage 2 opposite the road 3, an upright vane 65 is mounted for horizontal swinging movement by means of transverse bars 66 bolted thereto, as at 67, and hinged, as at 68, to an upright 69 rising from a plate 70 bolted, as at 72 to an extension 71 on the cross beam 6. A pull chain 73 operatively connects the van 65 to the vane 51. The functions of the vanes 51, 65 will presently be explained.

Referring now to the operation of the invention, a vehicle, not shown, approaching the gate closure 1 from either side thereof will ride over the chain 47 at that side of said closure and depress the chain flat against the anchor bar 40 therefor, or against the road 3, as the case may be, thereby causing the chain to exert a sudden pull on the crank 48 to which it is connected. As best shown in Figure 4, in the gate closing position of the gate closure 1, the ends of the chains 47 which are attached to the cranks 48 slide downwardly, under the influence of gravity, against the spacers and abutments 49 so that pull exerted by said chains will be effective against the cranks 48. Therefore, initial pull of either chain 47 will initially rock the sleeve 42

to which the chain is connected by the crank 48 and so as to swing the gate closure 21 counter-clockwise as viewed in Figures 1, 2, 3, 4 and 6. However, such initial rocking of the sleeve 42 will first swing the latch lifting lever 43 rearwardly sufficiently to release the latch bar 34 and thereby unlatch the gate closure 1. During this operation, the related one of the restoring levers 44 will be swung upwardly and rearwardly by said sleeve 42 to increase the tension of its connecting spring 45. The latch bar 34 through engagement with its stop lug 37 will then swing said gate closure 1 upwardly with sufficient momentum to cause it to swing through substantially 180° into horizontal open position in which it extends away from the road 3, as shown in Figure 3. As the gate closure 1 swings upwardly the vane 51 swings downwardly and forwardly from normal position and retards such swinging of said closure by wind resistance against said vane until said closure has swung through substantially an arc of 45° as shown in dotted lines in Figure 6. When said closure 1 swings into substantially vertical position, the vane 51 picks up and lifts the weight 60 so that after said closure 1 swings another 45°, substantially, the weight 60 overbalances said closure 1 to overcome its momentum as it reaches completely opened position and causes it to swing slowly back into its closing position for latching in a manner which will now be clear. As will be seen, the gate closure 1 is counterbalanced toward gate closing position through substantially 90° of return movement, after which the vane 51 releases the weight 60 and acts through wind resistance against the same to retard closing movement of said closure 1. Normally the vane 65 is set by hand broadside to heavy wind blowing in a direction to retard closing movement of the gate closure 1 so that it will be swung by such wind rearwardly and through its chain connection to the vane 51 assist in swinging said closure 1 closed by pulling on the vane 51. A counterweight 75 is slidably mounted on the lower front end portion of the closure frame 21 for setting by a set screw 76 to variably counterbalance the closure 1 as an aid in preventing sudden closing of said closure. By shortening or lengthening the chain 61, counterbalancing of the gate closure 1 may also be varied, as occasion may require. A particular feature of my invention is that after the gate closure reaches substantially vertical position when swinging open, the ends of the pull chains 47 may slide downwardly on the cranks 48 so that upward and forward swinging of said cranks during further opening movement of said closure 1 will not tighten the chains 47 and thereby lift the same off the road 3 before the vehicle has completely passed over said chains. When it is desired to slide the skid carriage 2 for moving the gate closure 1 from one position to another, the arms 40 may be swung upwardly and fastened in any suitable manner to said carriage in upswung out of the way position.

The springs 45 and sleeve restoring levers 42 restore the sleeves 42 to normal position during final closing movement of the gate closure 1 so that the latch bars 34 may assume latching position and the chains 47 will be held up for depressing by vehicles.

The foregoing will, it is believed, suffice to impart a clear understanding of my invention, without further explanation.

Manifestly, the invention, as described, is susceptible of modification, without departing from

the inventive concept, and right is herein reserved to such modifications as fall within the scope of the appended claims.

Having described the invention, what is claimed as new is:

1. In combination, a carriage adapted for positioning at one side of a road, a gate closure for closing and opening the road, means supporting said closure on said carriage for vertical swinging into opening and closing position including a horizontal closure supporting shaft fixed to said gate and journaled for rocking by swinging of said closure from closing position, a sleeve rockable on said shaft, means operatively connecting said sleeve to said closure to swing said closure from closing position upon rocking of said sleeve, vehicle operative means extending across the road and operatively connected to said sleeve to rock said sleeve upon operation of said vehicle operative means, a member fixed to said closure and shaft and swingable from a normal position by said closure and shaft upon swinging of said closure from closing position, and a weight suspended from said sleeve in the path of swinging of said member and spaced from said member when said member is in normal position for delayed action lifting by said member to counterbalance said closure toward closing position.
2. The combination according to claim 1, and a wind pressure responsive vane pivotally mounted on said carriage and connected to said member to return the member to normal position and thereby swing said closure toward closing position.
3. In combination, a carriage adapted for positioning at one side of a road, a gate closure for closing and opening the road, means supporting said closure on said carriage for vertical swinging into opening positions including a journaled horizontal rock shaft fixed to said closure, a sleeve rockable on said shaft, vehicle operative means extending across the road and operatively connected to said sleeve for rocking said sleeve by operation of said vehicle operative means, and lost motion means operatively connecting said sleeve to said closure with a delayed action for swinging said closure into opening position by rocking of said sleeve.
4. The combination according to claim 3, said last named means comprising a lug on said closure, and a closure latching bar pivoted on said closure and swingable on its pivot from latching position into engagement with said lug.
5. The combination according to claim 3, said vehicle operative means comprising a horizontal road engaging arm extending laterally from said carriage across the road, a flexible pull member extending across the road in suspended position with one end fixed to said arm, and a skeleton crank fast on said sleeve and having the other end of said pull member slidably connected thereto to create a slack in said flexible member after rocking of said sleeve.

FREDERICK W. BOSCH.
